UNITED STATES PATENT OFFICE.

DONALD J. CAMPBELL, OF MUSKEGON HEIGHTS, MICHIGAN, ASSIGNOR OF ONE-FOURTH TO GEORGE W. CANNON, OF MUSKEGON, MICHIGAN.

CORE BOX.

Application filed February 10, 1921. Serial No. 443,738.

To all whom it may concern:

Be it known that I, DONALD J. CAMPBELL, a citizen of the United States of America, residing at Muskegon Heights, in the county of Muskegon and State of Michigan, have invented certain new and useful Improvements in Core Boxes; and I do hereby declare the following to be a full, clear, and exact description of the invention, such 10 as will enable others skilled in the art to which it appertains to make and use the same.

This invention relates to a core box mould for the moulding of cores from green sand of irregular shape, though not necessarily limited to any prescribed shape. The core box is particularly adapted for the moulding of cores for pistons of engines such as are used in internal combustion engines, and 20 with the same the cores may be moulded, several at one time in the core box of my invention, and withdrawn therefrom and used to serve as the drag portion of a completed mould, with which a properly moulded cope is to be used to complete the mould. The invention, primarily, is directed to a relatively simple construction of box in which green sand cores may be formed and moulded, and the same quickly withdrawn 30 therefrom, so that production on a large scale may be had. A further object of the invention is to construct a core box of this character, in which different sizes and shapes of piston cores may be made by merely changing certain parts of the box to correspond with the piston core desired, the master box being constructed to detachably receive the special fittings for the different types and sizes of cores, this rendering it possible to provide cores for many 40 different sizes and types of pistons without having a complete core box for each size or type. A still further object of the invention is to provide the construction with ready means for freeing the box from the cores after the same are moulded so that the disconnection or drawing of the cores from the core box may be quickly and easily accomplished. These and many 50 other objects and purposes, together with novel constructions and arrangements of parts for attaining the same, will appear as understanding of the invention is had

from the following description, taken in connection with the accompanying drawings, illustrating a preferred form of construction, in which drawings,

Fig. 1 is a plan view of the core box of my invention.

Fig. 2 is a transverse vertical section taken substantially on the broken lines 2—2, of Fig. 1.

Fig. 3 is a horizontal section on the plane of line 3—3, of Fig. 2.

Fig. 4 is a similar section of line 4—4, of Fig. 2.

Fig. 5 is a vertical section on the plane of line 5—5, of Fig. 1.

Fig. 6 is an elevation of the base member of the core box.

Fig. 7 is a vertical transverse section through the core box, showing the same inverted and the parts separated as required for the removal or withdrawal of the cores therefrom.

Fig. 8 is a perspective view of one of the halves of the master box, four of which halves are used in the construction of core box shown.

Fig. 9 is a perspective view of one of the halves of the side forms for a piston core, the same being detachably connected with the master box halves.

Fig. 10 is a perspective view of a detachable head form for the heads of the piston cores.

Fig. 11 is a longitudinal vertical section through one of the screw sleeves used in the construction.

Fig. 12 is an end elevation thereof.

Fig. 13 is a fragmentary side elevation, parts being in section, of a side of the core box illustrating the two part journal for the operating screw shaft of the construction, and

Fig. 14 is a perspective view of a core mould for pistons made with the core box of my invention.

Like reference characters refer to like parts in the different figures of the drawings.

In the construction of the core box, an outer housing or casing of metal is provided, rectangular in cross section at its upper portion and having parallel sides 1 and 105 ends 2. A plate 3 is located against the

upper edges of said housing, and is connected thereto by screws 4. This plate has four openings 5 therethrough as shown. A base plate 6 of circular outline is located in the lower portion of the housing or casing and is provided with a downwardly extending annular flange 6^a which fits within the lower circular portion of the casing. At four points, directly under each opening 5 in the upper plate 3, depressions 7 are made in base plate 6 in which head members 8 are seated, being detachably connected and secured in the depressions by screws as shown in Fig. 2. The head members 8 are provided with ribs 8^a on their upper sides, but this is not any feature of the invention, said head members being variously formed in accordance with the shape of cores wanted for the pistons. An annular rib 9 is cast integral with base plate 6 around each depression 7, the purpose of which will later appear.

In the outer sides of the flange 6^a of the base plate, a plurality of inclined grooves or slots 10 are cut, four being shown, though this may be varied. A ring 11 is mounted in the lower part of the housing around the flange 6^a, lying under an inwardly projecting rib 12 of the casing, and held thereagainst by a securing ring 13 which is attached at the lower edges of the lower circular portion of the housing by screws 14. Rollers 15 project inwardly from the ring 11 into the cam grooves 10. An outwardly projecting operating handle 16 is connected to the ring 11, passing through an elongated slot 17 made in the lower circular portion of the housing, and which is indicated at 18.

It is obvious that by moving the handle 16 back and forth in the slot 17, ring 11 may be turned, this serving to raise and lower base plate 6, due to the formation of the cam grooves 10 and the rollers 15 running therein. Two inwardly extending lugs 19 project toward each other from opposite sides of the housing to which depending guide pins 20 are secured, the same passing downwardly through openings 21 formed in inwardly projecting lugs 19^a on the flange 6^a of the base plate. The pins serve to guide the base plate in its movements and make such movements uniform, obviating binding and the like.

A screw shaft 22 is mounted on the casing, extending between and through ends 2 thereof. At its intermediate portion each side of the middle thereof, said shaft is equipped with two oppositely threaded screws 23 and 24, and adjacent its ends with two more oppositely threaded screws 23^a and 24^a. The screws 23 and 23^a are of like character, and the same is true of screws 24 and 24^a. The ends of the shafts are mounted in roller bearings 25 held between divid-

ed journal boxes having upper and lower parts 26 connected to the ends 2 of the outer housing, whereby the screw shaft and parts attached thereto may be readily placed in or taken from the housing by merely removing the upper halves 26 of said journals. The shaft at one end has a handle 27 for manual operation and at the other end a collar 28 whereby endwise movement of the shaft is prevented.

An exteriorly threaded sleeve 29 is threaded on to each of the screws 23^a and 24^a, and a similar sleeve formed of upper and lower halves 30 is located around each of the screws 23 and 24. On each of the sleeves thus constructed one half of a master box member is mounted. There are four of these members indicated at 31, a threaded opening 32 being made centrally through each for the reception of the sleeve 29 or 30. At each end, each member 32 is formed with a semicylindrical recess, the walls to which are indicated at 33, and at the lower ends and on the outer sides of said walls, the same are cut or otherwise formed with a downwardly extending inward taper, as shown at 34, conforming to the shape on the inner sides of the annular ribs 9 heretofore described. Each member 31 at its upper side is provided with a flange 35 rectangular in outline and adapted to be positioned immediately under the upper plate 3 of the outer housing, the edges of said flange being disposed between said plate 3 and under guide ribs 35^a projecting inwardly from sides 1 of the housing, as shown in Fig. 5.

The inner sleeves are divided longitudinally for purposes of assembling the parts which otherwise could not be accomplished unless the shaft 22 was divided at its middle. The halves of sleeves 30 are placed in proper position on their screws 23 and 24, and the two inner halves 31 of the master boxes threaded to position thereon against the lock nuts 30^a. The outer halves 31 are then threaded on to their sleeves 29 and the sleeves in turn threaded on to their screws 23^a and 24^a, after which the bearings 25, handle 27 and collar 28 are attached, the whole assembly being then placed in the outer housing on the lower halves 26 of the journals, the upper halves being then secured in place.

In practice, before placing the assembly within the outer housing, the particular core form which is to be used, may be placed within the cylindrical parts 33 of the master boxes. These may be of various forms. As shown, two halves 36 of a piston core form are placed in opposite master box forms 33 and secured thereto by screws 36^a, which are readily removable to permit changes of core forms. The forms are for piston cores having inwardly projecting lugs 37 extending toward each other; and adjacent their lower

ends and on their inner sides, the core forms 36 are provided with grooves 38 into which the edges of ribs 8^a of the heads 8 are adapted to seat when the boxes are closed.

- 5 In the operation of the core box, the same is placed with the plate 3 at the upper side and sand is entered into the spaces bounded by members 8 and 36, being rammed or otherwise compressed to proper density 10 for moulds. The sand may be entered in any desired manner, either by hand or by compressed air as designed by me, the construction for accomplishing which is the subject matter of an application for Patent Ser. No. 15 443,739, filed Feb. 10, 1921, separate and distinct from the present core box construction. The core box may be turned over, being shown with oppositely projecting trunions 39 for mounting the same to turn on 20 a horizontal axis on a suitable support, prior to which turning the sand is struck level with the surface of the plate 3 and a board or similar member 40 clamped against said plate. After the box is turned over, handle 25 27 is grasped and the shaft 22 turned to separate the two master box members 31 of each pair of members, base plate 6 having first been elevated through operation of handle 16, as previously described so as to free 30 the ends of parts 33 from the ribs 9. The elevation of the base plate draws the ribs 8^a from the core 41 in each of the four cores formed, and the separation of the master box halves carries the core forms 36 with 35 them, drawing the lugs 37 from the cores leaving the cavities 42 in the sides thereof, the same as the drawing of the ribs 8^a left the slots 43 in the core. This movement of the master box halves away from each other, 40 leaves the cores free for drawing from the core box, which may be done by unclamping strike plate 40 and lowering it from the core box in any suitable manner. The openings 5 in the plate 3 are large enough to 45 freely pass the cores formed, and the sand which has filled such openings makes a base 44 for the cores where the same rest on the plate 40. The parts of the core box may be returned to closed position, then the entire 50 box turned back to original position and the operation repeated, the process being indefinitely repeated until a desired number of green sand cores are obtained. This construction of core box is particularly useful 55 and practical for the quantity production of cores for pistons, but is not limited to use for the production of the one type of core. The cores formed may comprise the drag of the complete mould, a proper cope being placed 60 thereover. The rapidity of operation of the box is a valuable feature, it being evident that quantity production is dependent upon quick acting mechanisms in moulding as well as in other arts. The use of the same 65 construction of box for different types of

work or different sizes thereof, merely requiring the changing of the immediate core forms in the master boxes is a further valuable feature of the invention. The construction is strong and durable, fully capable of 70 withstanding the heavy duty to which it is subjected in service, it being particularly safeguarded against separation of the core forms under pressure such as is induced by packing or compressing the sand therein to 75 the necessary density. Many changes in detail of construction may be resorted to without departing from the invention which is defined in the appended claims, and I consider myself entitled to all such constructions as come within the scope of the claims. 80

I claim:

1. A device of the character described, comprising an outer casing, a plate having an opening therethrough covering the upper 85 side of the casing, a base plate movably mounted at the lower side of the casing, means to raise and lower said base plate, a divided master box located between the plates and consisting of two halves, means 90 for simultaneously moving said halves of the master box toward or away from each other, a two part core form detachably connected with the master box, one part of the form on each of the halves of the box, and 95 a core head member detachably connected to the base plate directly below the opening in the upper plate, said master box when in closed position coming under said opening in the upper plate, substantially as and for 100 the purposes described.

2. A device of the character described, comprising an outer housing, a plate having a plurality of openings therethrough covering the upper side of the housing, a 105 base plate movably mounted at the lower side of the housing, means to raise and lower the base plate with respect to the housing, a plurality of master boxes located within the housing, each consisting of two halves, a single means for simultaneously moving the halves of all the master boxes toward or 110 away from each other, and core forms detachably connected to the halves of the master box and the base plate adapted to 115 come together and form a complete core mould when the halves of the master box are moved together and being located one under each opening in the upper plate, substantially as described.

3. A device of the character described, comprising an outer housing, a plate having openings therethrough covering the upper side of the housing, two part core side forms mounted one under each opening in the 125 plate, means for moving the parts of the core forms toward or away from each other, a base plate movably mounted in the lower portion of the housing, means for moving the same toward or away from the lower 130

ends of the core side forms, and core head forms attached to the base plate, one for each two part core side forms and associating therewith to complete the core form 5 when moved into conjunction therewith, one of said complete core forms being positioned under each opening in the upper plate.

4. In combination, an outer housing having parallel sides and ends at its upper 10 portion and of cylindrical form at its lower portion, a base plate having an annular downwardly extending flange located within the lower portion of the housing, said flange having cam slots cut therein, a ring mounted 15 within said lower portion of the housing around the flange, means projecting from the ring into said cam slots whereby on rotation of the ring the base plate is raised or lowered, means for manually turning 20 said ring, divided master boxes in the housing, a single means for moving the parts of each master box simultaneously toward or away from each other, and a plate covering the upper side of the housing provided with 25 openings therethrough under which the master boxes come when in closed position, substantially as described.

5. In combination, the elements in combination defined in claim 4, combined with 30 guide pins attached to and depending from the inner sides of the housing, said base plate having guide openings into which said pins extend, substantially as described.

6. In combination, an outer housing, a 35 plate having openings therein through which sand may be entered into the housing, a divided core mould within the housing having sides and a lower head into which the sand is pressed, means for moving the 40 sides away from each other or toward each other, and means for moving the head toward or away from the lower ends of said sides, whereby the core mould may be separated to permit removal of the core 45 formed, or the parts brought together for the operative completion of the mould, substantially as described.

7. In combination, an outer housing, a cover plate at its upper side having openings 50 therethrough, a base plate located in and closing the lower end of the housing, means for raising or lowering the base plate, a screw shaft rotatably mounted in and passing through the housing and provided 55 with a pair of oppositely threaded screws, master box members mounted on the shaft, one on each screw, and means for manually turning the screw to bring the said members together or move the same away from 60 each other, said members when brought together having sand receiving openings located directly under the openings in said cover plate, substantially as described.

8. The elements in combination defined 65 in claim 7, combined with an upwardly pro-

jecting flange on the base plate adapted to pass around the lower edges of the master box members when the same are brought together and the base plate moved toward the same, substantially as described. 70

9. The elements in combination defined in claim 7, combined with core side forms attached detachably on the inner adjacent sides of the master box members, and a core head form for each two core side forms attached to said base plate detachably and movable with the base plate into engagement with the ends of its associated core side forms, substantially as described. 75

10. In combination, an outer housing, a cover plate at its upper side having openings therethrough, a base plate located in and closing the lower side of the housing, means for raising or lowering the base plate with respect to the housing, a screw shaft 80 rotatably mounted in and passing through the housing and formed in its length with a plurality of pairs of oppositely threaded screws, master box members mounted in pairs on the pairs of oppositely threaded screws, a handle at one end of the shaft for manually turning the same to move the master box members toward or away from each other, said master box members when brought together enclosing openings coming 85 directly under the openings in the cover plate. 90

11. In combination, a housing having an upper rectangular portion and a lower cylindrical portion, a base plate of circular 100 form located in the lower part of the housing and provided with a downwardly extending annular flange in which a plurality of inclined cam grooves are cut, a ring around said flange and located between the same and the walls of the housing, a plurality of rollers rotatably mounted on and projecting from the ring into said cam slots, a handle attached to the ring and extending outwardly therefrom, said housing having a slot therein for the passage of the handle, a cover plate to the upper side of the housing having sand entrance openings therein, master box members mounted in pairs in the upper portion of the housing, means for 105 moving the members of a pair of master box members toward or away from each other, and means on the upper side of the base plate for engaging with the master box members at their lower edges when the same are in closed position to hold the same from separation from pressure of sand, substantially as described. 110

12. In combination, a piston core forming mechanism, comprising separable side members, means for mounting the same to bring them together or separate them a distance from each other, an end closing member movable toward or away from one end of the side members and means on said end 115 120 125 130

closing member engaging with the side member when brought to closed position to lock them against separation, substantially as described.

- 5 13. In combination, two separable side members, means for movably mounting the same to simultaneously move them toward or away from each other, said members when brought together in closed position
- 10 having an opening between them shaped in accordance with a mould core desired, means for manually operating said first means, an end closing member movably mounted adjacent one end of the side members and operable toward or away from said end of said members, means for manually moving said end closing member toward or away from said side members and means on the end closing member engaging with the side
- 15 members to hold them locked in closed position.
- 20

14. A machine for forming green sand cores comprising separable sides and an end core form, manually operable means for moving the sides toward or away from each other and the end form toward or away from one end of the sides, and means on said end closing member engaging with the side members to hold them in locked position, substantially as described. 25

15. A machine for forming green sand cores comprising two separable side members, means for moving the same toward or away from each other, and end member movably mounted to close the side members at one end or move away therefrom, a means for moving said end member and means on said end closing member engaging with the side members to hold them in 30 35 locked position, substantially as described. 40

In testimony whereof I affix my signature,
DONALD J. CAMPBELL.
